UNITED STATES PATENT OFFICE.

EDGAR E. PHINNEY, OF NEW YORK, N. Y., ASSIGNOR TO MONROE CALCULATING MACHINE COMPANY, OF NEW YORK, N. Y., A CORPORATION OF NEW YORK.

KEYBOARD-CLEARING MEANS FOR REGISTERS.

1,354,839.

Specification of Letters Patent.

Patented Oct. 5, 1920.

Application filed March 8, 1917. Serial No. 153,368.

To all whom it may concern:

Be it known that I, EDGAR E. PHINNEY, a citizen of the United States, residing at New York, in the county of New York and State 5 of New York, have made a certain new and useful Invention in Keyboard-Clearing Means for Registers, of which the following is a specification.

Figure 1 is a side view, with parts broken

10 away.

Fig. 2 is a section on the line 2—2, Fig. 1.

Fig. 3 is a section on the line 3—3, Fig. 1.

Fig. 4 is a detail fragmentary plan view 15 of a portion of the clearing means, showing the lever operated by actuation of the rotary cam.

The invention has relation to calculating machines, and particularly to improved means for releasing all depressed denominational keys at the end of the rotation of the operating shaft. Other objects and advantages 20 will hereinafter appear.

The invention consists in the novel construction and combinations of parts, as hereinafter set forth. Reference is made to applicant's co-pending application Serial Number 142190 for explanation of the parts of the machine not described herein.

In the accompanying drawings, illustrating 30 the invention, the numeral 2 designates the casing, 3 the numeral keys, arranged in a plurality of denominational series and having stems 17'. The key stems in any denominational series are held in position as depressed in the setting up of the problem, by a spring-pressed bar 19, common to the series and pivoted at 20, said bar engaging the shoulders 21' of the key stems for this purpose and, upon depression of the proper 40 key in said series, being operated to release a key depressed by mistake in the same series.

The crank handle is applicable to the end 45 of the operating shaft 14, said shaft having bevel gear connection 26 with a longitudinal shaft (not shown). The operating shaft being rotated once completely in either direction, to perform the required problem, it is necessary that the keys depressed in the denominational series of keys shall, during the latter portion of the shaft rotation, be restored to their original positions.

To this end is provided a slide 121, having

usually pin and slot connection 122 with the frame plate 122' and provided with extensions 123, each extension designed, upon operation of said slide, for engagement with a spring-pressed bar 19, common to a denominational series of keys, and thereby releasing said bar from the shoulders 21' of the key stems, said keys being then returned to normal position by the springs thereof.

Means are provided to move the slide 121 in one direction during the latter portion of the rotation of the operating shaft in either 55 direction, the preferred embodiment of said means being described as follows:

A lever 124 is fulcrumed intermediately of its length, upon a pin 126 of the framing, said pin having a head 127 spaced apart 70 from the lever, a coiled spring 128 surrounding said pin and being located between the head thereof and said lever. One end of the lever is provided with a guide roller 129, engaging a vertical slot 130 of the frame 75 plate 122' and an adjacent roller 131 designed, upon operation of the lever, for engagement with the cam-beveled end 121' of the slide 121, to move the same in one direction to release the depressed keys as stated, 80 said slide being then returned to normal position by the springs 19' of bars 19.

Upon the shaft 14 is loosely mounted a finger 132 having a head the sides of which are beveled oppositely at 133, 133'. The collar of one of the bevel gears 26 is provided 85 with a pin 134, designed for engagement with the finger 132, to turn the same therewith, said finger, at the end of the shaft rotation in either direction, having its bevel 133, 133' (according to the direction of rotation of the operating shaft) engaged with the beveled end 135 of the lever 124, and operating said lever to shift the slide as stated.

The lever 124 is capable of being moved 95 horizontally from the work end thereof, carrying the guide roller, as a fulcrum or center, to cause the opposite or power end of the lever to be moved to one side of the finger 132, so that said finger in its rotation 100 with the operating shaft will have no action upon said lever, as is required in the performance of problems in multiplication and in division. This lateral or horizontal movement of the lever is accomplished by a rotary cam 136, having a flat side 137 normally

in contact with one side of said lever, said cam in a quarter turn thereof, brought about by moving crank handle 138, having its cylindrical periphery 139 engaged with said lever, to move the same as stated.

5 Means are provided for the operation of the slide 121 and release of all depressed numeral keys at any time desired, independently of the rotation of the operating shaft 14, and consisting usually of a depressible key 140, having an extension 141 engaging one arm of lever 124, said key being returned to normal position by its spring 140.

10 Each bar 19 may be operated independently, to release all keys depressed in any denominational series, by means of a key 142, common to each series, said key having a stem 143, provided with a cam surface 144 similar to the cam surfaces 17² of the key 20 stem 17, leading to the shoulders 21 thereof, and being depressible to a more limited degree than the keys 3, so that it will not be engaged by the bar 19 and will always be at

once returned to normal position by its spring 145.

25

I claim:

Clearing means for the keyboards of calculating machines having operating members and series of spring-retracted keys movable to set up a problem, means for retaining said keys in set-up position, means for releasing the retaining means, including a lever having guide bearings in the frame of the machine, lying normally within and adjustable upon said bearing as a fulcrum out of the path of said operating members, and a clear key having a stem adjacent to said bearing and adapted to engage said lever in the normal or in the adjusted position thereof.

30 In testimony whereof I affix my signature in presence of two witnesses.

35 EDGAR E. PHINNEY.
